UNITED STATES PATENT OFFICE.

EMMETT J. CAIN, OF LODI, CALIFORNIA.

SIGNAL-OPERATING MECHANISM.

Application filed April 1, 1926. Serial No. 98,948.

This invention relates to improvements in signaling devices to be used on motor vehicles to take the place of hand signals; my principal object being to provide an electric operating mechanism for a signal arm so arranged that the arm may be moved to and maintained at a number of different positions corresponding to those assumed by the human arm when the latter is used for signaling purposes.

A further object of the invention is to construct the device in such a manner that the signal arm moves very quickly and easily without having to overcome any appreciable force of gravity at any position and consequently requiring but a small consumption of current in its operation. The operation of the mechanism does not depend upon complicated and delicate moving parts and there is nothing in its construction which should break down or fail to function even after long service.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawings similar characters of reference indicate corresponding parts in the several views:

Fig. 1 is a cross section of the mechanism, taken in a plane adjacent one end of the same.

Fig. 2 is a front view of the device partly in section.

Fig. 3 is a diagram of the electric circuits used in connection with the mechanism.

Referring now more particularly to the characters of reference on the drawings the numeral 1 denotes a tubular housing, adapted to be mounted in a fixed position and to be disposed in a horizontal plane longitudinally of the vehicle. This housing has end caps 2, both said caps and the housing 1 being of non-magnetic material. Turnably mounted in the caps 2 is a shaft 3, to which, between the caps, is fixed a stem 4 having attached thereto a signal arm 5, the stem projecting radially from the shaft and housing 1, through a circumferential slot 6 in the latter. The arm may be of any suitable design, but I preferably intend to use a hollow

one to receive an electric light and having translucent faces so that the arm may be artificially illuminated at night.

Secured to the member 1 and projecting outwardly therefrom are longitudinally extending magnets which comprise cores 7 and windings 8 thereabout. The cores are radially disposed relative to the shaft in spaced relation to each other and project practically the full length of the housing 1. The outer ends of the cores are exposed, as are the inner ends thereof, the latter ends facing inwardly of the inner face of the housing 1. There are preferably four of these magnets arranged in spaced relation about the housing 1 on the opposite side thereof from the slot 6 and set 45 degrees apart, to correspond to a similar number of positions of the signal arm.

Fixed on the shaft 3 inside the housing 1 is a longitudinal armature 9 to cooperate with the inner ends of the magnet cores. An external armature 10, radially aligned with the armature 9, is arranged to cooperate with the outer ends of the magnet cores.

These armatures are connected to the shaft to form a magnetic unit therewith by means of arms 11 extending between said shaft and the armature 10 on the outside of the caps 2. The magnets are disposed relative to said armatures and to the signal arm so that when the signal arm is in a downward and vertically disposed position, the armatures are aligned with the uppermost magnet core. When the signal arm is at its opposite limit of movement, or at an upward 45 degree angle (a position denoting a right turn), the armatures are then aligned with the lowermost magnet core. When the armatures are aligned with the intermediate magnet cores the signal arm lies in a downward 45 degree position, denoting "stop" or "slow", or at a horizontal position denoting a left turn.

Disposed alongside the armature 10 on each side thereof and in spaced and parallel relation thereto are other armatures 12 concentric with the shaft 3. These armatures are connected at their ends of the armature 10 by non-magnetic strips 13. The armatures 12 are spaced 22½ degrees from the armature 10, so that when the latter is aligned with any magnet core, the armatures 12 are disposed intermediate adjacent magnets.

One end of the magnet windings are

grounded, the other ends of the windings being connected to individual and separated contacts 14. These contacts are mounted on a common switch panel 15 and are arranged in successive order corresponding to that of the different magnets. These contacts are arranged to be engaged in succession by a strip 16 mounted on a lever 17 which is pivoted on the panel concentric with the line of contacts, the strip 16 being connected to the battery 18 of the car. The length of the strip 16 is such that with the rotation of the lever, said strip engages any one of the contacts before breaking from the previous one. The armatures 9, 10 and 12 on one side of the shaft 3, and the signal arm on the other, are so designed that the weight of the opposed parts is balanced as nearly as possible.

In operation assuming that the signal arm is in its lowermost or neutral position, as shown in Fig. 1, and that it is desired to cause the signal arm to move to a downward 45 degree position, as shown in dotted lines; the switch lever 17 is moved past the first contact 14 (corresponding to the upper magnet) to the second contact, which corresponds to the second magnet. The first and second magnets will then be energized in succession and if the switch lever is left on the second contact the corresponding magnet will of course remain energized while the first one has become deenergized. This energizing of the second magnet initially draws the adjacent armature 12 theretoward, until said armature alines with the magnet core. By that time the double armatures 9 and 10 are within the sphere of influence of said magnet and will be attracted theretoward with a force greatly in excess of that offered by the armature 12. The armatures 9 and 10 will therefore move into alinement with the magnet core and will remain so alined until the magnet is deenergized. The signal arm being rigidly connected to the armature structure of course moves in conjunction with the latter.

If the signal arm is to be moved to some other and higher position, the switch lever 17 is successively engaged with and moved past the various contacts 14 until the one corresponding to the desired magnet and signal position has been reached. With this movement of the switch lever the magnets will be successively energized and deenergized and the armatures will be successively attracted towards and will pass by the different magnets until the furthest one energized has been reached. On account of the counter-balancing of the signal arm and armature structure, said structure is very sensitive and is easily moved. Hence an instant energizing of the magnets is sufficient to cause the structure to turn, and the setting of the signal arm to any position to be ac-

complished almost instantaneously with but little consumption of current. Each magnet being energized before the previous one is deenergized, the signal arm is held from possibly dropping back from a position previously reached and the movement of the signal arm in a continuous direction, corresponding to a continuous movement of the switch lever, is therefore obtained.

When the signal is to be returned to neutral position, the switch lever is moved in the opposite direction past the various contacts, causing the magnets to be successively energized and deenergized in the reverse direction. This causes the other armature 12 to be first attracted toward the various magnets with the successive energizing thereof followed by the double armatures 9 and 10, so that a continuous turning movement of the armatures and signal arm is had until the signal is in its lowermost position and the switch is opened.

The uppermost magnet comes into service only to draw the signal arm to its final downward position, in the event that the signal arm structure is so nicely balanced that the signal arm does not tend to drop of itself. The outer armature 12 also is only used during the retracting or return movement of the signal arm. The device may however be mounted in a casing as indicated at 19 and set out in the open in any suitable location.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention as defined by the appended claim.

Having thus described my invention what I claim as new and useful and desire to secure by Letters Patent is:

An operating mechanism for a signal comprising a shaft on which to mount the signal, an armature mounted in connection with the shaft and projecting from one side thereof, a plurality of relatively fixed magnets to attract the armature, said magnets being disposed between the shaft and armature and arranged in spaced relation to each other and concentric with the shaft, another armature on the shaft between said shaft and the magnets and radially alined with the first named armature, an additional armature disposed to one side of the first named armature, and means for mounting said additional armature in non-magnetic connection with the shaft.

In testimony whereof I affix my signature.

EMMETT J. CAIN.
